CLAIM

The ornamental design for a marker light for oversized cargo, as shown and described.

DESCRIPTION

FIG. 1 is a front, right side and bottom perspective view of a marker light for oversize cargo showing my new design;

FIG. 2 is a front elevational view thereof on a reduced scale;

FIG. 3 is a right side elevational view thereof on a reduced scale, the left side elevational view being a mirror image;

FIG. 4 is a top plan view thereof on a reduced scale; and,

FIG. 5 is a bottom plan view thereof on a reduced scale. The rear elevational view is plain and unornamented with the exception of the four equal length vertically disposed ribs shown in FIGS. 1, 3, 4 and 5. The power cord for the design is shown in varying positions throughout the drawing figures due to its flexible nature.
